US0D1031162S

(12) **United States Design Patent** (10) **Patent No.:** **US D1,031,162 S**
(45) **Date of Patent:** **** Jun. 11, 2024**

(54) **IPL HAIR REMOVAL DEVICE**

(71) Applicant: **Shenzhen BSX Technology Electronics Co., Ltd**, Shenzhen (CN)

(72) Inventors: **Qingzhong Zhang**, Shenzhen (CN); **Chunhua Xu**, Haimen (CN)

(73) Assignee: **Shenzhen BSX Technology Electronics Co., Ltd**, Shenzhen (CN)

(**) Term: **15 Years**

(21) Appl. No.: **29/863,754**

(22) Filed: **Dec. 22, 2022**

(30) **Foreign Application Priority Data**

Sep. 13, 2022 (CN) 202230602352.X

(51) **LOC (14) Cl.** **28-03**

(52) **U.S. Cl.**

USPC **D28/44.1**; D24/209

(57) **CLAIM**

The ornamental design for an IPL hair removal device, as shown and described.

DESCRIPTION

FIG. 1 is a front perspective view of an IPL hair removal device, showing our new design;

FIG. 2 is a rear perspective view thereof;

FIG. 3 is a front view thereof;

FIG. 4 is a rear view thereof;

FIG. 5 is a top view thereof;

FIG. 6 is a bottom view thereof;

FIG. 7 is a left side view thereof; and,

FIG. 8 is a right side view thereof.

The broken lines in the drawings illustrate the portions of the IPL hair removal device, which form no part of the claimed design.

1 Claim, 8 Drawing Sheets
